Des 1082

Hiram B. Musgrave, of Cincinnati, Ohio
Letters Patent. No 1082. Dated. Feb. 13. 1859.

The schedule referred to in these Letters Patent, and making part of the same.

To all whom it may concern:

Be it known that I, Hiram B. Musgrave of Cincinnati
Hamilton County Ohio have invented a certain new design a Portable Gauze Gas Burner for Cooking Heating &c. which design is represented in the accompanying drawings making part of this specification.

Fig. 1. is an elevation of the said burner and

Fig. 2. a perspective view of the same. —

I claim as new and of my invention.

A design for portable gauze Gas Burners, represented in the accompanying drawings.

For testimony of which Ihereunto set my hand

Exod
S. M. P.

Witnessed.
